(57) CLAIM

The ornamental design for a coffee table, as shown and described.

DESCRIPTION

FIG. 1 is a top, front perspective view of a coffee table, showing my new design;

FIG. 2 is a bottom, rear perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof; and,

FIG. 9 is an enlarged view of detail 9 of FIG. 2.

The broken line showing of the coffee table is for the purpose of illustrating portions of the coffee table and form no part of the claimed design.
